CLAIM

The ornamental design for a fluid container with pressure seal, as shown and described.

DESCRIPTION

FIG. 1 is an upper perspective view of a fluid container with pressure seal;

FIG. 2 is a lower perspective view thereof;

FIG. 3 is a front view thereof;

FIG. 4 is a left side view thereof;

FIG. 5 is a top view thereof; and,

FIG. 6 is a bottom view thereof.

The back view and the right side view are substantially mirror images of the front view and the left side view, respectively.
